FIG. 2

INVENTOR
CHARLES W. HARROLD

BY HIS ATTORNEY

Philip P. Rich

UNITED STATES PATENT OFFICE

1,935,051

PRINTING-PRESS

Charles W. Harrold, Cleveland, Ohio, assignor
to Harris-Seybold-Potter Company, Cleveland,
Ohio, a corporation of Delaware

Application August 11, 1931. Serial No. 556,361

17 Claims. (Cl. 101—174)

My invention relates particularly to sheet-fed rotary printing-presses, and more especially to a multicolor rotary press equipped with a double-sized impression cylinder.

- 5 The objects of my invention are, among other things, to provide a novel and simplified printing-press of this type which is equipped with two separate feeders which forward the sheets alternately from separate piles to the impression cylinder at the same point and from a common feed cylinder that receives the sheets from both feeders. After printing the sheets are transferred from the impression cylinder to a common delivery cylinder from which the sheets are alternately taken by separate deliveries running at approximately half speed, and such printed sheets are then delivered on separate piles from the two separate deliveries operated at such reduced speeds.
- 10 It has been found that the primary limiting factor of the operating speed of rotary printing-presses resides in the maximum speed at which the printed sheet can be delivered to the pile flat and properly jogged, since automatic sheet feeders as a rule will operate at higher speeds than pile deliveries. One of the objects of my invention is to provide a press with separate deliveries whereby it is possible nearly to double the output of the press without increasing the speed at which the printed sheet reaches the delivery piles.

15 A further novel feature of my invention is found in mounting the pair of plate cylinders in eccentric bushings with alternate tripping mechanism operated and controlled by the press whereby it is possible to print one form on sheets advanced from the first feeder and another form on sheets from the second feeder alternately by using the alternate throw-off and throw-on of the two plate cylinders (half the diameter of the impression cylinder) upon each revolution of the impression cylinder, or, on the other hand, print two forms on the same side of each sheet as in the ordinary, two-color press.

20 A further novel feature resides in having the feed cylinders that take the sheets from the separate feeders rotate at the face speed of the printing cylinders, but the separating and registering devices for each feeder operate at half-speed, which arrangement gives double time for front and side registration of the sheets before gripped by the feed cylinders to be carried to the impression cylinder for printing. In combination with the half-speed deliveries mentioned, my improved press enables the operator

after receiving sheets in each pile delivery from its particular feeder again to run the same pile through the same feeder under the same registering conditions as is required for high-class color work, and in conjunction with these advantages both the feeding and delivery of the sheets are operating approximately at half the printing speed.

25 With these and other objects and advantages in view, my invention comprises the structural lay-out and construction of the operating parts forming my improved printing-press herein shown and hereinafter to be described as a preferred embodiment of my invention.

30 In the drawings, Figs. 1 and 2 are side elevation views of my improved press shown as a composite; Fig. 1 shows the two feeders and the printing members while Fig. 2 shows the two deliveries, the sheets passing from right to left through the press as a whole shown in the combined figures.

35 Similar numerals refer to similar parts throughout the two figures.

40 Referring to Fig. 1, the impression cylinder 3 rotates in the direction of the arrow and carries the two impression surfaces 4 and 5 provided with the usual grippers 6 and 7 respectively. The impression cylinder 3 is double-sized or twice the diameter of the two superposed plate cylinders 8 and 9 of half the diameter of the impression cylinder 3 and having their shafts mounted in the eccentric bushings 10 and 11 respectively. These bushings 10 and 11 are provided with the arms 12 and 13 actuated by rods 14 and 15 respectively, these rods being actuated and controlled in the usual way to trip the plate cylinders 8 and 9 from the impression cylinder 3 alternately as required. The plate cylinders 8 and 9 rotate in the direction of the arrows as shown, and are provided with the usual inking form rollers 16. The particular form of inking mechanism for the cylinders 8 and 9 is not a part of this invention and so is not further indicated in the drawings.

45 On the right of Fig. 1 are the two separate feeders A and B arranged in staggered relation to each other. The upper feeder A comprises the feed-table 17 with pile of paper sheets 18 above which is the sheet separator 19 which may be a combining roll or suction feed cylinder to advance the successive sheets along the tapes 20 between feeding rollers 21 and 22 to the front and side registering devices indicated by the rollers 23 and 24.

50 Any type of sheet separator for advancing the successive sheets from the pile 18 may be used, the separator 19 as shown serving as a diagram-

matic illustration of such device. The sheets having been registered at the forward end of the tapes 20 are successively taken by the grippers 25 on the first feed cylinder 26 (of the same size as the plate cylinders 8 and 9) and then are transferred to the second feed-cylinder 27 having the grippers 28 which deliver the sheets to the grippers 6 or 7 of the impression surfaces 4 or 5 of the impression cylinder 3 in suitable timed relation with these impression surfaces. The feed cylinders 26 and 27 revolve at the face speed of the plate cylinders 8 and 9 in the direction shown by the arrows. In the feeder B the sheets from the pile 29 on the feed table 30 are forwarded by the sheet separator 31 to the tapes 32 between feeding rollers 33 and 34 to the front and side registering devices 35 and 36 from which the sheets are taken by the grippers 28 of the feed cylinder 27 and delivered to the impression cylinder 3 in the same manner as sheets advanced and delivered by the feeder A.

Below the impression cylinder 3 is the delivery cylinder 37 having the grippers 38 which take the successive sheets from the grippers 6 and 7 of the impression cylinder and then transfer same alternately to the separate deliveries C and D arranged like the feeders A and B in staggered relation to each other. The two deliveries C and D are constructed substantially alike. Referring to both Figs. 1 and 2 and the upper delivery C, the V-belt carriers 40 pass in pairs around the reel 41 having the grippers 42 which coat with the grippers 38 (Fig. 1) to take the sheets from the delivery cylinder 37 and carry same beneath the rubber drive wheels 43 superposed above the reel 41 and belts 40, the sheets passing to the left (Fig. 2) between the belts 40 and superposed endless tapes 44 at surface speed.

Such sheets then overtake the grippers 45 on the endless delivery chains 46 (seven sets of grippers 45 being shown in Fig. 2) that pass around the sprockets 47 and 48; these chains 46 are adapted to be driven approximately at half speed relatively to the belts 40. The chains 46 carry the sheets to the left and the grippers 45 are opened in the usual way to deposit the sheets on the pile 49.

Referring again to Figs. 1 and 2, the delivery D comprises the V-belt carriers 50 passing in pairs around the reel 51 having the grippers 52 which coat with the grippers 38 on the delivery cylinder 37 at a point lower than for the delivery C (Fig. 1). The rubber drive wheels 53 located above the reel 51 press the sheets against the belts 50 and such sheets travel at surface speed toward the left beneath the endless tapes 54. The sheets then overtake the grippers 55 on the endless delivery chains 56 (four sets of grippers 55 being shown in Fig. 2) that pass around the sprockets 57 and 58 and are driven approximately at half speed relatively to the belt-carriers 50. The delivery chains 56 carry the sheets on their lower runs with the grippers 55 opening in the usual way to deposit the sheets on the pile 59. The rollers 60 and 61 are idlers supporting the belts 40 and 50 respectively adjacent the sprockets 47 and 57.

It will be noted that in both deliveries C and D, the sheets are taken from the delivery cylinder 37 at face or surface speed of the press, and after a short run on the V-belt carriers 40 and 50 respectively at such surface speed are fed into the grippers 45 and 55 respectively mounted on delivery chains 46 and 56 respectively for delivery at slow

or reduced speed upon their respective piles 49 and 59.

In like manner the sheets are advanced to the press by the feeders A and B at approximately half the printing speed which factor is important in giving double time for front and side registration of the sheets before being taken by the feed cylinders 26 and 27 respectively. Furthermore by using the eccentric bushings 10 and 11 on the single-sized plate cylinders 8 and 9 and double-sized impression cylinder 3 with alternate tripping of these plate cylinders according to well-known mechanism that need not be described, it is possible for the pressman to print one form on the sheets from feeder A and another form on sheets from feeder B alternately by using alternate throw-off and throw-on of the plate cylinders 8 and 9 in each revolution of the impression cylinder 3, or print two forms (on plate cylinders 8 and 9) on the same side of each sheet.

The operation of my improved printing-press has been sufficiently set forth in the foregoing description, and the advantages derived from the use of this press may be shown from the following: Assuming that 6,000 sheets are to be printed, 3,000 sheets would be placed in each feeder A and B and run through the press from these feeders only once to result in securing the 6,000 sheets printed in two colors, or 12,000 printed impressions with only one registration of plates on the cylinders 8 and 9. Furthermore in both forms of operation which have been referred to when the press is delivering 6,000 sheets per hour, the sheet separators and registering devices in both feeders A and B are operating at only 3,000 sheets per hour, but the feed cylinders 26 and 27 are rotating at twice this speed, each taking a sheet from its respective piles 18 and 29 once in two revolutions. The face speed of all the cylinders comprising the press proper is the same, being 3,000 for the double-sized cylinders and 6,000 for the single-sized cylinders, but with the sheets slowed down on the delivery chains 46 and 56 to be delivered at approximately the same speed as they were forwarded to the feed cylinders 26 and 27 for printing from the feeders A and B.

It is obvious that sheet detectors and their associated trip mechanisms as commonly used in sheet-fed rotary presses may be embodied in my press, but such structural details are not shown as being well-known in the art, and therefore need not be explained.

My invention, in its broader aspects, is not limited to the particular construction and arrangement of cylinders and other associated parts shown, as many changes may be made without departing from the scope of the invention and without sacrificing the chief advantages derived from its use in a rotary press.

I claim as my invention:—

1. In combination a printing couple comprising an impression cylinder having a plurality of impression surfaces and a like plurality of printing members coacting therewith, a plurality of feeding devices for advancing sheets alternately to a gripper feed cylinder to be taken therefrom by said impression cylinder, a delivery cylinder, and a like plurality of deliveries taking the printed sheets alternately from said delivery cylinder.

2. In combination a printing couple comprising an impression cylinder having a plurality of impression surfaces and a like plurality of printing members coacting therewith, a plurality of feeding devices for advancing sheets alternately to a

- gripper feed cylinder to be taken therefrom at a common point on the impression cylinder; a delivery cylinder, and a like plurality of deliveries taking the printed sheets alternately from said delivery cylinder. 5
3. In combination a printing couple comprising an impression cylinder having a plurality of impression surfaces and a like plurality of printing members coacting therewith, a plurality of feeding devices for advancing sheets alternately to a gripper feed cylinder to be taken therefrom by said impression cylinder, a delivery cylinder, and a like plurality of deliveries taking the printed sheets alternately from different points on said delivery cylinder. 10
4. In combination a printing couple comprising an impression cylinder having a plurality of impression surfaces and a like plurality of printing members coacting therewith, a plurality of feeding devices for advancing sheets alternately to a gripper feed cylinder to be taken therefrom at a common point on the impression cylinder, a delivery cylinder, and a like plurality of deliveries taking the printed sheets alternately from different points on said delivery cylinder. 15
5. In combination a pair of plate cylinders and a double-sized impression cylinder having two impression surfaces coacting with said plate cylinders, two separate means for feeding sheets alternately to a gripper feed cylinder to be taken therefrom by said impression cylinder at a common point, a delivery cylinder coacting with the impression cylinder, and two separate deliveries for taking the printed sheets alternately from said delivery cylinder. 20
6. In combination a pair of plate cylinders and a double-sized impression cylinder having two impression surfaces coacting with said plate cylinders, two separate means for feeding sheets alternately to a gripper feed cylinder to be taken therefrom by said impression cylinder at a common point, a delivery cylinder coacting with the impression cylinder, and two separate deliveries for taking the printed sheets alternately from said delivery cylinder and depositing same at approximately half the speed of said delivery cylinder. 25
7. In combination a pair of plate cylinders and a double-sized impression cylinder having two impression surfaces coacting with said plate cylinders, two separate means for feeding sheets alternately to a gripper feed cylinder to be taken therefrom by said impression cylinder, a delivery cylinder coacting with the impression cylinder, and two separate deliveries for taking the printed sheets alternately from said delivery cylinder. 30
8. In combination, a pair of plate cylinders and double-sized impression cylinder having two impression surfaces coacting with said plate cylinders, two separate means for feeding sheets alternately to a common feed cylinder to be taken therefrom by said impression cylinder, and sheet separators for advancing sheets to said sheet feeding means operating at approximately half the speed of said common feed cylinder. 35
9. In combination, a pair of plate cylinders and a double-sized impression cylinder having two impression surfaces coacting with said plate cylinders, a delivery cylinder coacting with said impression cylinder, and two separate deliveries for taking the printed sheets alternately from said delivery cylinder and depositing same at approximately half the speed of said cylinders. 40
10. In combination, a pair of plate cylinders and a double-sized impression cylinder having two impression surfaces coacting with said plate cylinders, two separate means for feeding sheets alternately to a common feed cylinder to be taken therefrom by said impression cylinder, a delivery cylinder, and two separate deliveries taking the printed sheets alternately from different points on said delivery cylinder. 45
11. In combination, a printing couple comprising a double-sized impression cylinder having two impression surfaces and a pair of single-sized plate cylinders coacting with said impression surfaces, a gripper feed cylinder to deliver sheets to said impression cylinder, and two separate means for feeding sheets in alternate succession to said gripper cylinder, two sheet separators for advancing sheets to said sheet feeding means, said sheet separators operating at approximately half the speed of said cylinders. 50
12. In combination, a printing couple comprising a double-sized impression cylinder having two impression surfaces and a pair of single-sized plate cylinders coacting with said impression surfaces, a gripper feed cylinder to deliver sheets to said impression cylinder, another gripper feed cylinder delivering sheets to said first feed cylinder, and two separate means for feeding sheets in alternate succession to said gripper cylinders, two sheet separators for advancing sheets to said sheet feeding means, said sheet separators operating at approximately half the speed of said gripper feed cylinders. 55
13. In combination, a printing couple comprising a double-sized impression cylinder having two impression surfaces and a pair of single-sized plate cylinders coacting with said impression surfaces, two separate means for feeding sheets alternately from separate piles to a gripper feed cylinder to be taken therefrom by said impression cylinder at a common point, a gripper delivery cylinder adapted to take the printed sheets from said impression cylinder at a common point, and two separate deliveries for taking the sheets alternately from said gripper delivery cylinder and depositing same on separate piles. 60
14. In combination, a printing couple comprising an impression cylinder having a plurality of impression surfaces and a like plurality of printing members coacting therewith, a plurality of feeding devices for advancing sheets alternately to a gripper feed cylinder to be taken therefrom by said impression cylinder, said feeding devices operating at a speed slower than that of said gripper feed cylinder, a delivery cylinder, and a like plurality of deliveries taking the printed sheets alternately from said delivery cylinder, said deliveries depositing said sheets at a speed slower than that of said delivery cylinder. 65
15. In combination, a printing couple comprising an impression cylinder having a plurality of impression surfaces and a like plurality of printing members coacting therewith, a plurality of feeding devices for advancing sheets alternately to a gripper feed cylinder to be taken therefrom by said impression cylinder at a common point, said feeding devices operating at a speed slower than that of said gripper feed cylinder, a delivery cylinder taking the printed sheets from said impression cylinder at a common point, and a like plurality of deliveries taking the printed sheets alternately from said delivery cylinder, said deliveries depositing said sheets at a speed slower than that of said delivery cylinder. 70
16. In combination, a printing couple comprising

4

ing an impression cylinder having a plurality of impression surfaces and a like plurality of printing members coacting therewith, a plurality of feeding devices for advancing sheets alternately to a gripper feed cylinder to be taken therefrom by said impression cylinder, said feeding devices operating at a speed slower than that of said gripper feed cylinder, a delivery cylinder, and a like plurality of deliveries taking the printed sheets alternately from different points on said delivery cylinder, said deliveries depositing said sheets at a speed slower than that of said delivery cylinder.

17. In combination, a printing couple comprising an impression cylinder having a plurality

of impression surfaces and a like plurality of printing members coacting therewith, a plurality of feeding devices for advancing sheets alternately to a gripper feed cylinder to be taken therefrom by said impression cylinder at a common point, said feeding devices operating at a speed slower than that of said gripper feed cylinder, a delivery cylinder taking the printed sheets from said impression cylinder at a common point, and a like plurality of deliveries taking the printed sheets alternately from different points on said delivery cylinder, said deliveries depositing said sheets at a speed slower than that of said delivery cylinder.
